BRAKE ARRANGEMENT FOR INBOARD
RAILWAY CAR TRUCKSJames C. Settles, Columbus, Ohio, assignor to The
Buckeye Steel Castings Company, Columbus,
Ohio

Application July 15, 1947, Serial No. 761,037

5 Claims. (Cl. 188—53)

1

This invention relates to inboard railway car trucks, that is, to car trucks in which the side frames are positioned inwardly of the supporting wheels; and the primary object of the invention is to provide a truck of this type having side frames arranged for single standard type brakes with certain parts passing under the inclined tension members of the frames.

Another object is to provide a truck of this character in which the body brake is connected to the medial portion of a horizontal lever which is slidably supported by the side frames and is operatively connected at its ends to the brakes for the wheels of the truck.

With the foregoing objects outlined and with other objects in view, which will appear as the description proceeds, the invention consists in the novel features hereinafter described in detail, illustrated in the accompanying drawings, and more particularly pointed out in the appended claims.

In the drawings:

Fig. 1 is a fragmentary top plan view of a truck in accordance with the invention, and with the brake shoes and heads removed.

Fig. 2 is a side elevation of the same.

Fig. 3 is an enlarged transverse vertical sectional view of a detail.

Referring to the drawings, 4 designates side frames having pedestals 5 at the ends thereof for the reception of roller bearing units 6 in which the axles 7 of the wheels 8 are journalled. Each side frame preferably includes a compression member 9 and tension members 10, the latter converging downwardly and merging with a spring seat member 11. It will be noted from Fig. 1 that the medial portions of the side frames are widened, and the ends thereof are arranged inwardly of the wheels.

Each side frame has a conventional bolster opening, and a spring plank 13 extends into the opening. It will be noted from Fig. 3 that the spring plank extends entirely through the bolster opening of each side frame and projects beyond the outboard side thereof, and the plank may be interlocked with the spring seat member by a spud and hole connection, indicated at 14.

Springs 15 rest on the spring plank and support a bolster 16 having upstanding portions 17 at its ends, extending through vertical windows 18 in the compression members of the side frames. The upstanding members are provided with damping wedges 19 which frictionally engage the vertical surfaces 20 of the bolster guide columns of the side frames.

2

The parts 4, 13, 15, 16 and 19 may be similar in construction to those parts in an application which I filed jointly with L. E. Furniss, Serial No. 761,038, on July 15, 1947, now Patent No. 2,594,079, dated April 22, 1952.

In accordance with the present invention, the body brake mechanism is connected to the medial portion 21 of a horizontal beam 22, slidably mounted in horizontal slots 23 of the side frames.

10 The end portions of the lever terminate in trunnions 24 from which vertical levers 25 are pivotally suspended. The medial portions of these levers are pivotally connected at 26 to brake shoes 27 arranged to engage the treads of certain of the

15 wheels 8 at opposite sides of the truck.

The lower ends of the levers 25 are connected by a transverse horizontal tie rod 28, positioned beneath one of the inclined tension members 10 of the opposed side frames.

20 Safety straps 29 are secured to the tension member, as indicated at 30, and as the tie rod extends through them, they will prevent the tie rod from falling in the event of breakage of parts.

A spreader link 30a extends lengthwise at each 25 side of the truck and is provided at one end with a plurality of apertures 31, either of which is designed to receive an end of the tie rod 28 to facilitate adjustment.

The link extends through a safety hanger bracket 32 which may be secured to the spring plank and spring seat member of each side frame, as indicated in Fig. 3.

35 At the dead end of each braking system, at each side of the truck, the side frame is provided with an integral bracket 33 having a series of holes 34, any one of which may receive a retaining pin 35 from which a lever 36 is pivotally suspended at each side of the truck. The levers 36 are pivotally connected at their medial portions, as indicated at 37, to brake shoes 38 which engage the treads of the other wheels at opposite sides of the truck, and the levers 36 have their lower ends connected to the ends of a horizontal tie rod 39 which extends through safety hanger brackets 40.

40 In operating such brake arrangement, a pull at 21 from the body brake is equally divided between the tops of the two vertical live levers 25 at opposite sides of the truck. This pull causes the levers 25 to rotate in a clockwise direction, thereby 45 moving the brake shoes 27 against a pair of oppositely disposed wheels of the truck. After any initial clearance between the shoe and wheel has been taken up as above, the levers 25 rotate about the pinned connections 26, and due to this rotation, force spreader links 30a toward the opposite

end of the truck. This motion of the links 30a rotates levers 36 at the dead end in a clockwise direction about the pins 35 and thereby forces the shoes 38 at the dead end against the adjacent wheels, thus applying the brake.

As the tie rods 28 and 39 extend across the truck between the lower ends of the opposite vertical levers, they will equalize, between the two sides of the truck, the forces which act in a direction across the truck due to the shoes being forced against the coned tread of the wheels. Owing to the fact that the angle of coning on each wheel-tread is slight, the force which it produces is also small, but this force would tend to make the shoes move outwardly on the wheel treads when the brakes were applied, if the tie rods were not present. This movement might become appreciable as slack due to wear accumulated in the brake arrangement. Each tie rod has a trunnion at each of its ends which serves as the pins to connect the spreader links 30a to the lower ends of the levers 25 and 36. As before stated, the safety straps 29, 32 and 40 prevent the links 30a or the tie rods from falling on the rails in case of breakage of some part which normally supports the links and tie rods.

As the horizontal lever 22 is directly supported by the side frames, it can form a support for the live end portion of the braking system at each side of the truck. The dead end of the brake systems is supported through the pinned connections 35.

From the foregoing, it is believed the construction, operation and advantages of the invention may be readily understood, and I am aware that changes may be made in the details disclosed without departing from the spirit of the invention, as expressed in the following claims.

What I claim and desire to secure by Letters Patent is:

1. A brake rigging for a four-wheel railway car truck comprising, wheel supported axles having journals inboard of the wheels, two truss type side frames with ends thereof mounted directly on said journals inboard of the wheels, a compression member on each side frame, a tension member on each side frame including portions inclined downwardly from ends of the compression member, said compression members each having a slot therein, a horizontally disposed brake actuating beam of greater length than the span between the side frames extending through said slots, vertical levers pivotally connected to the ends of said beam outboard of said side frames depending from the ends of said beam and supported thereby, brake shoes pivotally connected to medial portions of said levers engageable with two wheels of the truck, a tie rod of greater length than the span between the side frames extending transversely of the truck under inclined portions of the tension members and pivotally connected to lower ends of said vertical levers, spreader links arranged at opposite sides of the truck each pivotally connected to an end of said tie rod and each pivotally connected to a lower end of one of said vertical levers, additional vertically disposed levers having their upper ends pivotally connected to the respective compression members at outboard sides thereof, a second tie rod of greater length than the span between the side frames extending transversely of the truck under other inclined portions of the tension members and pivotally connected to other ends of the spreader links and pivotally connected to lower

ends of the second levers, and brake shoes pivotally connected to the medial portions of the second levers engageable with the other two wheels of the truck.

2. A brake rigging for a four-wheel railway car truck comprising, wheel supported axles, a pair of truss type side frames with ends thereof mounted directly on said axles inboard of the wheels, a compression member forming a part of each side frame, a spring seat on each side frame, downwardly converging tension members supporting said spring seat, a horizontally disposed brake beam of greater length than the span between the side frames extending transversely of the truck overlying and resting on said compression members, vertical levers pivotally connected to ends of said beam outboard of the respective side frames and depending therefrom, brake shoes pivotally connected to medial portions of said levers engageable with two wheels of the truck, spreader links arranged at opposite sides of the truck each connected at one end to a lower end of one of said vertical levers, additional vertically disposed levers pivotally connected at their upper ends to said compression members at outboard sides thereof, means pivotally connecting lower ends of the second levers to the ends of the spreader links, said spreader links extending horizontally along outboard sides of the spring seats and below upper surfaces thereon, and brake shoes pivotally connected to medial portions of the second levers engageable with the other two wheels of the truck.

3. A brake rigging in combination with a four-wheel railway car truck comprising, two wheel supported axles having journals inboard of the wheels, a pair of truss type side frames with ends thereof mounted directly on said journals inboard of the wheels, a compression member forming a part of each side frame, a spring seat on each side frame, tension members on each side frame inclined downwardly from the ends thereof and connected to opposite ends of the spring seat, guide columns connecting the compression member and tension members of each side frame and providing a bolster opening therebetween in each side frame, a horizontally disposed brake beam of greater length than the span between the side frames extending transversely of the truck overlying and resting on said compression members at one side of the bolster, vertical levers pivotally connected to ends of said beam outboard of said side frames and depending therefrom, brake shoes pivotally connected to medial portions of said brake levers engageable with two wheels of the truck, a tie rod of greater length than the span between the side frames extending transversely of the truck under the inclined tension members of opposite side frames and through openings in lower ends of said vertical levers, spreader links arranged at opposite sides of the truck pivotally connected to the ends of said tie rod and to said levers, additional vertically disposed levers having their upper ends pivotally connected to said compression members at outboard sides thereof, a second tie rod of greater length than the span between the side frames extending transversely of the truck under the other inclined tension members and through openings in lower ends of the second levers, means pivotally connecting other ends of the spreader links to the second tie rod and to lower ends of the second levers, said spreader links extending hor-

izontally along outboard sides of the spring seats at opposite sides of the truck and below the bolster openings, and brake shoes connected to medial portions of the second levers engageable with the other two wheels of the truck.

4. A brake rigging for a four-wheel railway car truck comprising, two wheel supported axles having journals inboard of the wheels, truss type side frames with ends thereof mounted directly on said journals inboard of the wheels, a compression member forming a part of each side frame, tension members on each side frame inclined downwardly from the ends, a horizontally disposed brake beam of greater length than the span between the side frames extending transversely of the truck overlying and resting on said compression members, vertical brake levers pivotally connected to ends of said beam outboard of said side frames and depending therefrom, brake shoes pivotally connected to medial portions of said brake levers engageable with two wheels of the truck, a tie rod of greater length than the span between the side frames extending transversely of the truck under the inclined tension members of opposite side frames and through openings in lower ends of said vertical brake levers, spreader links arranged at opposite sides of the truck pivotally connected to the ends of said tie rod and to the lower ends of said levers, additional vertically disposed brake levers having their upper ends pivotally connected to said compression members at outboard sides thereof, a second tie rod of greater length than the span between the side frames extending transversely of the truck under the other inclined tension members and through openings in lower ends of the second brake levers, means pivotally connecting other ends of the spreader links to the second tie rod and to lower ends of the second brake levers, said spreader links extending horizontally along the outboard sides of the side frames, brake shoes connected to medial portions of the second brake levers engageable with the other two wheels of the truck, and safety hanger brackets carried by the tension members of the side frames through which the tie rods extend.

5. A brake rigging for a four-wheel railway car truck comprising, two wheel supported axles having journals thereon inboard of the wheels, a pair of truss type side frames with ends thereof mounted directly on said journals inboard of the wheels, a compression member forming a part of each side frame, a spring seat on each side frame, tension members on each side frame inclined downwardly from the ends thereof and connected to opposite ends of the spring seat,

guide columns connecting the compression member and the tension members of each side frame and providing a bolster opening therebetween in each side frame, a horizontally disposed beam of greater length than the span between the side frames extending transversely of the truck overlying and resting on said compression members at one side of the bolster, vertical levers pivotally connected to ends of said beam outboard of said side frames and depending therefrom at one side of the bolster openings, brake shoes pivotally connected to medial portions of said brake levers engaging with two wheels of the truck, a tie rod of greater length than the span between the side frames extending transversely of the truck under the inclined tension member of opposite side frames and pivotally connected to lower ends of said vertical levers, spreader links arranged at opposite sides of the truck pivotally connected to the lower ends of said levers and extending horizontally along outboard sides of the spring seats below said bolster openings, additional vertically disposed levers having their upper ends pivotally connected to said compression members at outboard sides thereof and depending along other sides of the bolster openings, a second tie rod of greater length than the span between the side frames extending transversely of the truck under other inclined tension members of opposite side frames and pivotally connected to the lower ends of the second levers, means pivotally connecting other ends of the spreader links to the lower ends of the second levers, and brake shoes connected to the medial portions of the second levers engageable with the other two wheels of the truck.
